LAMP SHADE AND MOUNTING THEREFOR

William E. Vogel, Los Angeles, Calif., assignor to
 Lighting Specialties, Inc., Los Angeles, Calif., a
 corporation of California

Application September 18, 1948, Serial No. 49,909

3 Claims. (Cl. 240—138)

1

This invention relates to a lamp shade and mounting therefor. Popularity of the little standing lamps, used mainly on dressing tables has created a heavy demand for sturdy, attractive and relatively inexpensive shades for use therewith.

It is an object of this invention to provide a lamp shade and mounting therefor which is attractive and sturdy but which can be inexpensively produced.

Shades of the type to which this invention relates must be mounted directly on the electric lamp bulb. The most general means used for this purpose has been a pair of circular wire loops engaging opposite sides of the bulb. These loops have been employed in many different ways either as an integral part of the wire frame of the shade or as an adapter connecting with screw collars on the shade provided primarily for screwing onto a socket.

Heretofore, when shanks formed on circular globe engaging loops were held together by a ring encircling the necks of the loops, the opposite ends of these shanks were welded to a wire ring embodied with the shade in order to anchor these shanks against the torque imposed thereon by the spring action of the loops in gripping a globe.

It is a further object of the invention to provide a shade and mounting therefor, the latter including bulb gripping loops as aforesaid, in which the shade is made entirely of plastic material, and therefore contains no wire ring to serve as a torque anchor for said shanks.

The invention is illustrated by way of example in the accompanying drawing in which:

Figure 1 is a view in top elevation showing the mounting as applied to the lamp shade.

Fig. 2 is a view in central vertical section taken on the line 2—2 of Fig. 1.

Fig. 3 is an enlarged fragmentary detailed sectional view taken on the line 3—3 of Fig. 2 and showing the details of construction of the lamp shade mounting.

Fig. 4 is a diagrammatic end elevational view of the mounting of the invention showing the bulb engaging loops thereof in full lines as relaxed and in broken lines as when these are sprung apart to admit an electric bulb therebetween for mounting the invention on said bulb. This illustrates the function of the torque anchors provided on the ends of the wire shanks which are held by saddle clips against rotation about the axes of such shanks to retain springiness in said bulb gripping loops.

Fig. 5 is an enlarged edge elevational view of

2

one of the saddle clips of the invention this being taken in the direction of the arrow 5 in Fig. 4.

Fig. 6 is an enlarged vertical sectional detailed view taken on the line 6—6 of Fig. 1.

Referring more particularly to the drawing, 10 indicates a frustoconical lamp shade which is preferably made of translucent material such as plastics. It is provided with a skirt 11 and a circular rib 12. This rib 12 at diametrically opposite sides is formed with a boss 12'. The skirt 11 may be embellished in any desired way to provide ornamentation and is designed to be mounted detachably on an incandescent light bulb. The mounting for the shade upon the bulb is designated at 13 and comprises two complementary loops 14 and 15 which are made of wire and are threaded through a ring 16. This ring is preferably made of flat stock so that it will be rigid. The opposite ends of the loops 14 and 15 terminate in shanks 17 and 18. These shanks lie parallel to each other and are formed with outward torque anchors 19 and 20, respectively, which are bent at right angles to the shanks 17 and 18 and are engaged by tangs 21 and 22, respectively, of a saddle clip 23. The body portion of the saddle clip 23 is formed with tangs 24 and 25, respectively, which may wrap around the shanks 17 and 18 and secure the shanks in position while holding the torque anchors 19 and 20 so that they project in opposite directions from each other and lie flat against the body of the saddle clip 23. The tangs 21 and 22 are formed integral with the body of the clip 23 and are folded upon said body, as shown in Fig. 4, so that the tangs will lie in a fixed spaced relation horizontally. Attention is also directed to the fact that the body portion of the saddle clip 23 and the tangs 21 and 22 are spaced vertically from each other to provide a recess 26 which may receive rib 12 and the diametrically spaced bosses 12' carried thereon.

In operation of the present invention the structure is formed as shown in the drawing and the mounting 13 is assembled as indicated particularly in Figs. 1, 3 and 4. When the mounting structure 13 is assembled as shown in the drawing the loops 14 and 15 may be flexed together in the ring 16. With the device thus compressed, one of the saddle clips 23 is brought to register with the annular rib 12 so that the top of the saddle rests upon the rib and the tangs 21 and 22 extend beneath the rib. The device is now allowed to expand to shift the other saddle clip 23 into a similar gripping relation with a diametrically opposite portion of the rib 12. The

saddle clips 23 are preferably applied so that the bosses 12' of the rib 12 register between the bent ends of the torque anchors 19 and 20 and thus hold the mounting in a centered position with relation to the shade.

It is to be noted that the saddle clips 23 not only provide gripping recesses 26 for receiving rib 12 and thereby assembling the mounting on the shade but they also (1) prevent rotation of the mounting as a whole relative to the shade on the axes of the shanks 17-18 and (2) anchor these shanks against their individually turning in response to the torque imposed thereon by the spring action of the loops 14 and 15 when spread to introduce a light bulb therebetween.

It is thus seen that I have produced an attractive plastic lamp shade having no metal therein, yet which is equipped with a mounting of the double wire loop type fulfilling all the requirements of spring action and stability and which may be built and assembled at a relatively low cost.

While I have shown the preferred form of my invention as now known to me, it will be understood that various changes may be made in combination, construction and arrangement of parts by those skilled in the art, without departing from the spirit of the invention as claimed.

Having thus described my invention, what I claim and desire to secure by Letters Patent is:

1. In a lamp shade adapted to be mounted directly upon an electric bulb, the combination of: a plastic lamp shade having a rib formed integral therewith to extend inwardly therefrom; a pair of spring wire bulb engaging loops; a ring uniting said loops by the terminal sections of the latter extending through said ring and being bent to form pairs of shanks extending from said ring to diametric opposite portions of said rib, the shanks of each pair lying side by side; torque anchors embodying end portions of said shanks bent therefrom in opposite directions; saddle clips, the body of each of which overlies a pair of said torque anchors and a portion of the adjacent pair of shanks; tangs bent from the body of each such clip to embrace the adjacent pair of shanks; and tangs bent from the body of each clip and passing around and under adjacent torque anchors and the adjacent portion of said rib whereby said tangs cooperate with said clip bodies in uniting said shade with the balance of said combination

and preventing substantial rotation of said anchors about the axes of said shanks.

2. A combination as in claim 1 in which bosses are provided on said rib at diametric opposite points on said shade to engage and center thereon the structure supported by the engagement of said clips with said rib as aforesaid.

3. In a lamp shade adapted to be mounted directly upon an electric bulb, the combination of: a plastic lamp shade having a rib formed integral therewith to extend inwardly therefrom; a pair of spring wire bulb engaging loops; a ring uniting said loops by the terminal sections of the latter extending through said ring and being bent to

15 form pairs of shanks extending from said ring to diametric opposite portions of said rib, the shanks of each pair lying side by side; torque anchors embodying end portions of said shanks bent therefrom in opposite directions; and a pair of

20 saddle clips each of which unites one of said pairs of shanks adjacent the torque anchors bent therefrom and embraces said torque anchors to prevent substantial rotation of said anchors about the axes of said shanks, there being a recess

25 formed in the extremity of each clip which recess lies in the plane of the adjacent torque anchors and is substantially co-extensive in length with said anchors, said recesses fitting and receiving said diametric opposite portions of said rib and said clips being forced into interlocking relation with said rib by the expansion of said spring wire loops.

WILLIAM E. VOGEL.
